BUNDLING STRAP

Richard S. Schwartz, Union, N.J., assignor to Thomas & Betts Corporation, Elizabeth, N.J.

Filed Mar. 17, 1970, Ser. No. 21,931

Term of patent 14 years

Int. Cl. D9—06

U.S. Cl. D9—252

FIG. 1

FIG. 2

FIG. 3

FIG. 4

FIG. 5

FIG. 6

FIG. 7

FIG. 8

FIG. 1 is a front perspective view of a bundling strap showing my new design;

FIG. 2 is a front elevational view thereof;

FIG. 3 is a side elevational view thereof;

FIG. 4 is a top plan view thereof;

FIG. 5 is a bottom plan view thereof;

FIG. 6 is a rear elevational view thereof;

FIG. 7 is a top plan view showing another embodiment of my new design;

FIG. 8 is a top plan view showing still another embodiment of my new design, with a portion of the strap being broken away for convenience of illustration; and

FIG. 9 is an enlarged, fragmentary sectional view taken on the line 9—9 of FIG. 4.

I claim:

The ornamental design for a bundling strap, substantially as shown and described.
